No. 791,789.

PATENTED JUNE 6, 1905.

C. S. HUNT.

ROAD SCRAPER.

APPLICATION FILED FEB. 27, 1905.

UNITED STATES PATENT OFFICE.

CLIFTON S. HUNT, OF MODOC, INDIANA.

ROAD-SCRAPER.

SPECIFICATION forming part of Letters Patent No. 791,789, dated June 6, 1905.

Application filed February 27, 1905. Serial No. 247,576.

To all whom it may concern:

Be it known that I, CLIFTON S. HUNT, a citizen of the United States, residing at Modoc, in the county of Randolph, State of Indiana, 5 have invented certain new and useful Improvements in Road-Scrapers, of which the following is a specification, reference being had therein to the accompanying drawings.

This invention relates to a road-scraper, and 10 particularly to a construction to prevent the lateral displacement of the frame of the machine due to the diagonal disposition of the scraper-blade.

The invention has for an object to provide 15 the frame at its front portion with a diagonally-disposed scraper-blade and at the rear with a trailer-blade disposed at an angle to the scraper-blade, so as to resist displacement of the frame.

20 Another object of the invention is to provide means for drawing the scraper and trailer blades toward each other, thus obtaining a deeper grip of the latter and throwing the weight of the frame thereon.

25 Another object of the invention is to provide an improved means for adjusting the scraper-blade and retaining it in its adjusted position for different conditions of use.

Other and further objects and advantages of 30 the invention will be hereinafter set forth, and the novel features thereof defined by the appended claims.

In the drawings, Figure 1 is a perspective of 35 the invention, and Fig. 2 a longitudinal section upon the line 2-2 of Fig. 1.

Like letters of reference refer to like parts in both figures of the drawings.

The letter A designates the platform or frame of the machine, which is suitably supported upon the axle A', provided with wheels A², by which it is supported. Beyond these 40 wheels rearwardly-extending brace-rods A³ are disposed and connected to the frame at A'. These rods are also provided with an angularly-disposed portion A⁵, lying in a vertical plane, to which the trailer-blade B is secured. At the front of the frame a scraper-blade C, of any desired material, is disposed and is supported by means of a lever C', connected there- 45 to by a link-joint C². This lever is pivotally

5 mounted upon a standard C³ of any desired form and is adapted to be held in its adjusted position by means of a vertically-disposed rack-bar C⁴, adapted to engage a tooth or lug C⁵, carried upon the lever C'. This rack-bar 55 is also provided with a guard-strip C⁶, extending about one face and the top thereof, to prevent the complete removal of the lever from the bar. This bar is also pivotally mounted 60 at C', so as to fold downward into the position shown by dotted lines in Fig. 1, and thus hold the free end of the lever in raised position to retain the scraper-blade in contact with the ground.

Any suitable draft means may be supplied 65 to the machine—for instance, a pole, as shown at C⁸, connected by rods C⁹ with the scraper-blade to apply the draft directly thereto. The draft is communicated from the blade C to the axle of the machine by means of links D and 70 D', each of which is provided at one end with a collar D² to fit upon the axle and at its opposite end with a swivel connection with the scraper-blade of any desired construction—for instance, as shown at D³. This swivel connection permits a longitudinal inclination of 75 the blade for the purpose of ditching or cleaning ditches already formed, and the blade may be so inclined by means of the operating-lever D⁴, pivotally mounted at D⁵ upon the upper end of the standard D⁶, extending from the axle and connected at its outer end D⁷ with one end of the scraper-blade, so as to elevate that end when the free end of the lever D⁴ is depressed.

For the purpose of drawing the scraper and trailer blades toward each other and thus cause a deeper hold of the latter in the ground, thus restraining the tendency of the frame to a lateral displacement, these blades are connected together by rods B' and B², connected to any suitable form of lever adapted to produce a simultaneous draft in the same direction upon each of the rods. I have shown one form of lever adapted for this purpose 90 comprising the cramp-lever B³, pivotally mounted at B⁴ in a bracket B⁵ and adapted to be held at its adjustment by means of the latch B⁶, engaging the ratchet-segment B⁷ upon the upper surface of the platform. It will be ob- 95 100

vious that a movement of this lever will produce a strain upon the rods drawing the scraper and trailer blades toward each other, thus forcing the same downward and removing the weight to some extent from the traction-wheels in order to obtain a better and deeper hold upon these blades to resist the lateral displacement caused by the diagonal disposition of the scraper-blade.

10. It will be obvious that changes may be made in the details of construction and configuration without departing from the spirit of the invention as defined by the appended claims.

Having described my invention and set forth 15 its merits, what I claim, and desire to secure by Letters Patent, is—

1. In a road-scraper, a frame supported upon an axle having wheels, a diagonally-disposed scraper-blade at the front of said frame 20 and connected to said axle, and a trailer mounted upon the rear of said frame at an angle to the scraper-blade.

2. In a road-scraper, a frame, a diagonally-disposed scraper-blade at the front thereof, a 25 trailer-blade at the rear of said frame disposed at an angle to the scraper-blade, and means for drawing said blades toward each other.

3. In a road-scraper, a frame, a diagonally-disposed scraper-blade at the front thereof, a 30 trailer-blade at the rear of said frame disposed at an angle to the scraper-blade, means for drawing said blades toward each other, and means for elevating and retaining said scraper-blade.

35. 4. In a road-scraper, a frame, a diagonally-disposed scraper-blade at the front thereof, a trailer-blade at the rear of said frame disposed at an angle to the scraper-blade, means for drawing said blades toward each other, means 40 for elevating and retaining said scraper-blade, and means for elevating one end of said scraper-blade.

45. 5. In a road-scraper, a frame, a diagonally-disposed scraper-blade at the front thereof, a trailer-blade at the rear of said frame, a cramp-

lever upon said frame, and connections from said cramp-lever to each of said blades.

6. In a road-scraper, a frame, a diagonally-disposed scraper-blade at the front thereof, a trailer-blade at the rear of said frame, a cramp-lever upon said frame, connections from said cramp-lever to each of said blades, and means for retaining said lever in its adjusted position. 50

7. In a road-scraper, a frame, a supporting-axle, traction-wheels for said axle, a scraper-blade pivotally mounted at the front of said frame by links extending from said axle, a raising-lever for said blade, and a rack-bar for retaining said lever in position. 55

8. In a road-scraper, a frame, a supporting-axle and traction-wheels therefor, a scraper-blade pivotally mounted at the front of said frame by links extending from said axle, a raising-lever for said blade, a rack-bar for retaining said lever in position, and a pivotal support for the lower end of said rack-bar to permit the same to swing into contact with said lever when its free end is depressed. 60

9. In a road-scraper, a frame provided with 70 an axle and traction-wheels, a scraper-blade disposed at the front of said frame, links pivotally mounted at one end upon said axle, and a swiveled joint between the opposite end of said links and the scraper-blade. 75

10. In a road-scraper, a frame provided with an axle and traction-wheels, a scraper-blade disposed at the front of said frame, links pivotally mounted at one end upon said axle, a swiveled joint between the opposite end of 80 said links and the scraper-blade, and an operating-lever pivotally supported upon said axle and connected at one end of said blade to elevate the same.

In testimony whereof I affix my signature in 85 presence of two witnesses.

CLIFTON S. HUNT.
